(57) **CLAIM**

The ornamental design for a housing cover, as shown and described.

DESCRIPTION

FIG. 1 is a front perspective view of a housing cover; FIG. 2 is a front view of the housing cover, as shown in FIG. 1;

FIG. 3 is a rear view of the housing cover, as shown in FIG. 1;

FIG. 4 is a top view of the housing cover, as shown in FIG. 1;

FIG. 5 is a bottom view of the housing cover, as shown in FIG. 1;

FIG. 6 is a side view of the housing cover, as shown in FIG. 1;

FIG. 7 is a side view, opposite the side view shown in FIG. 6, of the housing cover, as shown in FIG. 1;

FIG. 8 is a front perspective view of a housing cover, according to another preferred embodiment of this invention;

FIG. 9 is a front view of the housing cover, as shown in FIG. 8;

FIG. 10 is a rear view of the housing cover, as shown in FIG. 8;

FIG. 11 is a top view of the housing cover, as shown in FIG. 8;

FIG. 12 is a bottom view of the housing cover, as shown in FIG. 8;

FIG. 13 is a side view of the housing cover, as shown in FIG. 8;

FIG. 14 is a side view, opposite the side view shown in FIG. 13, of the housing cover, as shown in FIG. 8;

FIG. 15 is a front perspective view of a housing cover, according to another preferred embodiment of this invention; and,

FIG. 16 is a rear perspective view of the housing cover shown in FIG. 15.
